METHOD OF AND APPARATUS FOR COATING
FABRIC ON EITHER OR BOTH FACESHenry C. Bostwick, Coventry Township, Summit
County, Ohio, assignor to Akron Standard Mold
Company, Akron, Ohio, a corporation of Ohio

Application November 29, 1950, Serial No. 198,094

12 Claims. (Cl. 154—10)

1 The general purpose of this invention is to enable the application of a sheet of coating material to either one or to both sides of a sheet of fabric as the fabric is fed into the supply roll of a stock storing apparatus, commonly called a "servicer." In addition, the invention is designed to maintain a uniform tension of the material that is being fed into the servicer.

The invention is accomplished by passing a strip of fabric through feed rolls and by applying to the fabric, either at the top or bottom or both faces thereof, a layer of rubber or similar material and pressing such layer against the fabric so as to make it adhere thereto. I provide a coating mechanism carrying a roll or rolls of sheet rubber and having motor-driven pressure rolls to press the rubber onto the fabric and feed the fabric thus coated to the servicer.

As the fabric passes from the feeding rolls of the coater into the servicer, it falls in a bight or festoon and the extent of the festoon is utilized for controlling the operation of the servicer motor. Thus, if the fabric is being discharged from the coater at a rate faster than it would be fed into the servicer, the servicer motor is automatically stopped. This is accomplished by a floating roller in the bight which according to its position may actuate a switch-controlling circuit of the servicer motor. At the start of the operation the manually controlled motor of the coating mechanism is operated to feed a length of coated fabric sufficient for engagement by the feeding device of the servicer, but the servicer motor does not start until the roller in the bight has dropped down to a predetermined position.

In practice, the servicer motor is designed to run at a somewhat faster speed than the coater motor, in order to prevent the festoon from exceeding a certain maximum degree.

There is an additional switch for controlling the operation of the servicer motor, which operates to cut off the flow of current to the motor whenever the end of the coated strip is nearly wound up on the storage roll, thus enabling the ready attachment of a subsequent strip.

My invention includes the method of coating a fabric and supplying it to a stock storage device as above outlined and as more fully described hereinafter. It includes likewise the method of building a tire or band by the product of the coating device. It also includes the apparatus illustrated in the drawings hereof and explained in the description, which apparatus is useful in carrying out the above-outlined method and also embodies a number of novel features not specifically mentioned above but hereinafter fully set out.

2 In the drawings, Fig. 1 is a side elevation showing the association of the coating mechanism with a servicer and a tire making machine for a continuous operation; Fig. 2 is a side view on a larger scale of the coating mechanism and the feed control to the servicer; Fig. 3 is a vertical transverse section in offset planes indicated by the line 3—3 in Fig. 2; Fig. 4 is a vertical longitudinal section in offset planes indicated by the line 4—4 in Fig. 3; Fig. 5 is a fragmentary plan of the feeding portion of the coating mechanism, being a horizontal section taken on the plane indicated by the line 5—5 on Fig. 4; Fig. 6 is a fragmentary plan illustrating the roll-supporting brackets of the coating mechanism, being a horizontal section taken in a plane indicated by the line 6—6 in Fig. 2; Fig. 7 is a vertical section of a stock roll and its liner roll in the servicer; Fig. 8 is a wiring diagram for the motor which operates the intake mechanism of the servicer; Fig. 9 is a diagrammatic view illustrating several double-coated layers with intervening fabric, such as may be mounted on a storage roll or a band-building drum.

Referring first to Fig. 1 of the drawings, 1 indicates the coating apparatus, 100 the servicer and 200 a conventional drum such as used in building of tires or bands.

Briefly, and as hereinafter more fully explained, the coating mechanism has a base 10 from which rise standards 11 carrying, by suitable brackets 12 and 13, two supply rolls 15 and 16 of rubber strip and associated liner strip and two take-up rolls 17 and 18 for the freed liner strips. Intermediate of these two sets of rolls the standards 11 carry cross heads 14 and 19 (see Fig. 3) on which is mounted the mechanism for pressing the layers together and feeding the composite strip.

The fabric strip A is fed from a suitable source (not shown) through the coating apparatus, where a layer of rubber B pressed onto its upper surface or a layer B' pressed onto its lower surface, or both coatings are effected. After this, the composite strip designated C passes to the servicer where it is wound up on a suitable storage roll. The rubber layers B or B' on their respective rolls are interleaved by a strip of liner canvas which passes with the rubber layer to the fabric strip A, but after pressure is applied causing the rubber to adhere to the fabric is stripped from the rubber and passes, as indicated at D and D' to receiving rolls for such liners.

As the composite strip C enters the servicer a liner designated E (Fig. 7) is fed from a suitable liner roll and wound up with the composite

strip, as indicated in Fig. 7. This produces on the storage roll layers of fabric with rubber facing, the different layers being separated by the liner sheet of the servicer. The layers on the servicer rolls may be similar to that indicated in the diagram, Fig. 9, where E would indicate the liners.

The storage rolls and their associated liner rolls in the servicer comprise two sets, which are mounted in a turret adapted to be revolved 180° on a vertical axis. Thus one set of rolls, namely, the set at the left in Fig. 1, is in position to receive the stock while the other set at the right in this figure, is in position to allow the discharge to the building drum.

The servicer as shown may, for instance, be of the form shown and described in my Patent No. 2,242,810, issued May 20, 1941, and illustrated herein in Fig. 1, and in that case each set of stock rolls 101 and associated liner rolls 102 are mounted on endless chains 103 passing over sprocket wheels 104 on shafts 105 journaled in a turret 106. This turret is mounted on a vertical axis above a supporting frame 107. Suitable mechanism (not shown) is provided for turning the turret 180°.

A pair of motors 110 on the turret operate endless belts 111 which drive rollers 115 which may frictionally engage the lowermost stock rolls of the servicer and thus rotate such roll in the direction to wind up the composite fabric thereon, as in the left hand position of Fig. 1, or in the direction to unwind it as in the right hand position, where the composite fabric C' passes downwardly to the tire building drum 200.

Resting in the bight of the fabric C, as it passes from the coater to the servicer is a dancing roller 20 which is shown as mounted on arms 21 carried by a rock shaft 22 (Fig. 5) pivoted to the cross heads 14 and 19 of the coater. The shaft 22 carries a cam 23 (Fig. 2) which may actuate a switch 25 controlling the motor 110 of the servicer.

The composite fabric C, as it passes into the servicer, passes across a roller 120 carried by a rocking frame and pressed upwardly by a counter-weight 121. The fabric in being wound up on the servicer holds this roller depressed, as shown in Fig. 1, but when the strip has been nearly wound up on the storage roller the weight of the strip on the counter-weight roller is so reduced that the counterweight swings the roller upwardly. This movement opens a switch 125 also in circuit to the motor 110 to stop the winding operation. By properly setting the counter-weight on the teeter bar, the servicer may be stopped when the fabric still hangs down a foot or more onto the feed table 126, 127 of the servicer, so that the next ply may be readily spliced to it.

Fig. 8 is a wiring diagram illustrative of the circuit connections to the motor of the servicer. It will be seen that a circuit passes in series through a manual switch designated 26 through the switch 125 of the servicer and through the switch 25 of the coater. This manual switch, shown diagrammatically in Fig. 8, may conveniently comprise a push button device on the edge of the feed table 27 of the coater, shown as supported by the cross heads and a bracket 28 rising from the base 10.

In starting the operation, the fabric is led up the feed table 27 of the coater and coater motor 30 (Fig. 4) is energized by a manual switch 31 to feed a sufficient length of composite fabric

toward the servicer, so that this fabric may be then engaged at its far end to the intake of the servicer, passing in this course below the dancing roller 20 and over the roller 120. In this course the roller 20 is low enough in position so that it leaves the switch 25 closed. Now the manual switch 26 is closed, which actuates the motor 110 of the servicer to wind in the composite fabric. As the servicer, when operating, pulls in the composite strip somewhat faster than it is fed out by the coater, such operation shortens the festoon of the composite strip and thus raises the dancing roller to a point where it opens the switch 25, which stops the loading movement of the servicer.

It will be seen that the loading operation of the servicer is intermittent while the coater operates continuously, but by operating the servicer faster than the coater and periodically interrupting the operation by the festoon-controlled switch, applicant is able to make the ultimate progress of the composite strip substantially the same in the two machines.

I will now give a specific description of the coating mechanism by which the continuous discharge of the coated fabric is obtained, reference being had to Figs. 2 to 6 inclusive.

Mounted on each of the vertical standards 11 of the coater frame are the brackets 12 and 13 heretofore mentioned which carry the supply rolls 15 and 16 and the liner rolls 17 and 18. Each bracket is a compound member consisting of two leaves each having projecting ears 40 embracing a vertical pin 41 carried by supporting ears 42 and 43 projecting from the standard 11. In normal use, the bracket leaves align with each other and are locked in this position by notched latch bars 45 pivoted to the standard 11 and engaging the bracket leaves, as shown in Figs. 2 and 6.

Each bracket leaf 12 and 13 carries a pair of rollers 47 overlapping each other as shown in Figs. 2 and 6. Each of the supply and liner rolls is mounted on a square shaft 48 which has rounded end portions 49 resting in the space between the peripheries of the two rollers 47. The different rolls thus are retained in position by gravity and are free to rotate on the anti-friction bearing provided by the rollers 47, though all of the rolls are prevented from undue turning by momentum, by means hereinafter described.

Any stock or liner roll may be removed from the machine by endwise movement off of its shaft by merely releasing the corresponding latch 45 and swinging outwardly the corresponding leaf of the supporting bracket.

The feeding mechanism for the various layers which constitute the composite strip is carried by the frame cross heads 14 and 19. This feeding mechanism comprises six rollers, designated 51 to 56 respectively, arranged in three vertical pairs, of which one member as 51, 54 and 55 is a smooth surface metal roller and the other member as 52, 53 and 56 is covered with rubber or other yielding material. The shafts on which the rubber covered rollers are tightly mounted are journaled in the cross heads and carry driving sprocket wheels, as hereinafter explained. The smooth covered rollers 51, 54 and 55 are each mounted on rocker arms 61, 64 and 65 respectively, which are on rock shafts oscillatably mounted in the cross heads. These rock shafts carry at their outer ends rock arms 66, 67 and 68, as shown in Fig. 2. Connected to each of these rock arms is a piston rod 70 mounted in cylinders respectively

5

designated 71, 74 and 75. By admitting fluid to one end or the other of these cylinders the corresponding pistons are operated to rock the rock shafts to press the rollers 51, 54 and 55 respectively, toward their mates with the desired pressure.

The operation of the piston-rock arm mechanism is preferably effected by compressed air through suitable conduits 72 leading to opposite ends of the cylinders from three suitably manually operated control valves, each designated 76. These control valves may be conveniently mounted on a bracket 77 carried by the top cross member of the frame and each may be actuated by a convenient hand lever 78.

The fabric strip A extends between each pair of feed rolls as shown in Fig. 4. One rubber sheet designated B with its surmounting canvas liner D leads from the roller 15 downwardly and loops in a bight about the swinging roller 51 which by pressure, effected by the cylinder 71 and its piston and rock arm 66 affixes the rubber surface to the fabric strip A, while the liner D passes upwardly to its roll 17. Similarly, the rubber strip B', with an underlying liner sheet, passes upwardly from the roll 16 and extends in a bight over the smooth roller 54 and the liner D' passes downwardly to the take-up roll 18. This strip, therefore, provides for coating the undersurface of the fabric. The final pair of rollers 55, 56 are for feeding the composite strip composed of the fabric A coated on one or both sides.

The turning of the rubber faced rollers 52, 53 and 56, to effect the feeding operation above-mentioned is caused by an endless sprocket chain 80 which engages sprocket wheels 81 on the shafts of the three rollers and also a driving sprocket 82 geared with the motor 30. Suitable extra sprockets 83 and 84 are provided to divert the course of the sprocket chain and make a better engagement with certain of the sprocket wheels.

It will be seen that when the motor 30 is operated, each of the rubber covered rollers 52, 53, 56 is rotated, all in the direction to have their surfaces which are adjacent the smooth rolls moving toward the right in Fig. 4 to advance the strip.

As the same time that the strip is advanced as just described, the two take-up rolls 17 and 18 for the liners are rotated to wind in the liners D and D' as the same is freed on the discharge side of the rollers 51 and 54. This rotation of the take-up roll 17 is effected by a spring belt 85 looped about a pulley on the shaft of the roller 52 and a pulley on the shaft 48 of the take-up roll. Similarly the take-up roll 18 is rotated by a spring belt 86 passing about a pulley on the shaft of the roller 53 and a pulley on the shaft of the take-up roll 18.

It will be seen that when the motor 30 is operated all of the rolls of the three pairs of feed rolls are rotating and likewise the two take-up rolls so that the fabric with the liner is drawn from either the roll 15 or the roll 16 or both rolls simultaneously and pressed into contact with the fabric strip A and that such coated strip is given the final feeding movement by the rotating rollers 55 and 56, the rotating take-up rollers rolling up the liner as the feeding takes place. The spring belts 85 and 86 of the take-up rolls allow slippage to compensate for the increasing radius of such rolls as they become loaded.

However, whenever desired the liner rolls may be disconnected from the drive effected by the motor 30. This is accomplished by actuating one or the other of the shipper levers 87, Fig. 5, to

6

shift the corresponding driving pulley 57 or 58 out of engagement with a normally engaged driving head 59 tight on the shaft of the roller 52 or the roller 54 as the case may be.

To prevent undue rotation by momentum of the stock rolls 15 and 16 as the material is pulled from them by the driven take-up rolls, I provide a brake on each stock roll. These brakes consist of tension springs 90 and 91 extending in a U-course about pulleys 92 and 93 tight of the shafts 48 of the two stock rolls, such springs being anchored at their ends to stationary bars, as 94 and 95, projecting from the frame of the machine.

To keep the material centered on the stock rolls 15 and 16, I provide pairs of guides 96 and 97 to engage the edges of the stock. These guides are adjustable in and out by being threadingly mounted on a horizontal right-and-left hand screw. Such screw is shown in detail at 98 in Fig. 3 for the guides 96, and the screw for the guides 97 is similar. The screws may be turned as desired by cranks 99 on their ends.

As my coating apparatus may serve to charge all of the rolls of the servicer before the operation of the tire building drum has exhausted the delivery rolls, it may be convenient to have one coating machine serve a number of service machines. To effect this, I may provide supporting wheels 2 on axles 3 and 4 carried by the base 10 of the coater frame on its underside. These wheels track on rails 5 extending in a region at the front of the battery of servicers. On one of the wheel axles, I provide a sprocket wheel 6 connected by sprocket chain 7 with a driving sprocket on a motor 8 mounted on the frame 10. The operation of this motor, under the control of a suitable switch, not shown, propels the entire coating apparatus in one direction or the other as desired. This same provision allows the coater to be rolled out of the way when it is desired to feed uncoated fabric into the servicer.

It will be seen that I have provided a comparatively simple coating apparatus suitable for use with one or more servicers, with the feed to the servicer automatically controlled.

The control of the motor of the servicer by a dancing roller in the festoon of the discharged composite strip allows the continuous operation of the coating apparatus and the corresponding intermittent operation of the servicer, so that the composite strip may be wound up in the servicer as fast as discharged by the coater. One of the advantages of this operation is that one operator takes care of feeding the stock into the coater and attending to the servicer.

My apparatus serves to press a layer of rubber or similar adhering material snugly onto either side of a strip of fabric, or onto both sides at the same time, and to feed such composite layer to the adjacent servicer, where the same may be wound up with a smaller member of liner sheets than formerly.

By coating both sides of the fabric so that such composite layer may be placed as a unit on the drum for building the band or tire with interposed strips of uncoated fabric, indicated at E in Fig. 9, I reduce the number of rolling down operations at the edge of each layer, commonly called "stitching," and increase the speed of building up the band or tire.

I claim:

1. A system of applying one or more layers of coating material to a sheet of fabric during the passage of the fabric towards a motor driven roll upon which it is wound, comprising pressing

the layer against the unwound portion of the fabric and feeding such composite strip in a festoon to the motor driven roll, providing an electric switch for energizing the driving motor of the roll and controlling the switch by the position of a floating member supported in the bight of the festooned composite strip.

2. An apparatus for applying a strip to either the upper or under face of a fabric strip comprising means for holding two spaced rolls of the material to be applied, an intermediately located feeder mechanism for the fabric strip, and roller means operatively disposed adjacent each face of the fabric strip for coaction in directing a sheet to be applied from one roll to one face of the fabric strip and a sheet to be applied to the other face from the other roll to contact with the fabric strip while the same is being advanced.

3. A fabric coating apparatus comprising a base, a pair of standards rising therefrom, means carried by said standards for holding rolls of rubber strip one spaced above the other, cross heads carried by the standards on the intermediate regions between the rolls, two pairs of coacting feeding rollers carried by the cross heads whereby one of the strips to be applied may be looped around one of the rollers of the first pair and the strip to be applied to the other face may be looped around the other roller of the second pair, and means for feeding a fabric strip past the two pairs of coacting rollers and between the rubber strips.

4. In a machine for applying a rubber strip to a fabric strip, the combination of a roll mounted on a fixed axis, a coacting roll mounted between a pair of rock arms and movable about a fixed axis toward and from the fixed roll, a piston and cylinder couple, one member of which is connected with the rock arms to shift the movable roll about the rock arm axis, means for controlling the pressure in the cylinder, whereby variable pressure may be obtained on a strip of material extending about the movable roll in contact with the fabric and means for rotating one of the rolls of the pair to advance the composite strip.

5. The combination of a frame, a roller therein mounted on a fixed axis, mechanism for rotating said roller, a coacting roller mounted on a rocking frame for movement toward and away from the fixed roller, a piston-and-cylinder mechanism for operating the rocking frame about the axis whereby a strip of rubber looped around the movable roller may be pressed against a strip of fabric between the rollers, the driving of the fixed axis roller serving to cause the rotation of both rollers and the advancement of the composite strip.

6. The combination of a standard, two pairs of rolls carried thereby, the rolls of each pair being one above the other, the lower roll of one pair being on a fixed axis and the upper roll of the other pair being on a fixed axis and the other rolls of the two pairs being movable, means for guiding a fabric strip successively between the rolls of the two pairs, means for holding rubber strips in loops respectively about the movable rolls of the two pairs, and mechanism for operating the two movable rolls to press the rubber strip extending about the movable roll against the fabric strip and feed the composite strip.

7. The combination of a frame, two pairs of rollers carried thereby, the rollers of each pair being located one above the other, means for positively driving the lower roller of one pair

and the upper roller of the other pair, piston-and-cylinder mechanisms for actuating the other two rollers of the pairs, means for carrying two rolls of sheet rubber with adjacent liner sheets in wound up form respectively above and below said sets of rollers, whereby a sheet and liner from the upper roll may be looped about the lower face of one of the movable rollers and the strip and liner from the other roll may be looped about the upper face of the other movable roller, means for winding up the liner from the discharge side of the movable roll, a pair of piston and cylinder mechanisms for operating the two movable rollers, to press the two rubber strips against the fabric strip, and a pair of manually operated valves for controlling the two piston and cylinder mechanisms.

8. The combination of a frame, two pairs of coacting rollers carried by the frame, the rollers of each pair being one above the other, the lower roller of one pair being on a fixed axis, the upper roller on the other pair on the fixed axis, the other rollers on the two pairs being carried by rocking frames, means for supporting rolls of rubber above and below the said rollers, whereby a rubber strip from one roll may be looped around the underside of the upper movably carried roller and a rubber strip from the lower roll may be looped around the upper side of the under movably carried roll, mechanism for rotating the two fixed axis rolls, and mechanism for pressing the two movable rolls toward the fixed axis rolls to coat the fabric strip on both sides and feed the same forwardly.

9. In an apparatus for coating fabric with a rubber strip comprising a roller on a fixed axis, a roller on a rocking frame adapted to be moved towards and away from the fixed roller for coaction therewith, means for supporting a roll of rubber and adjacent liner, whereby such rubber strip and its liner may be looped about the movable roller, a roller for taking up the liner after the same has been freed from the pressure rollers, mechanism for pressing the movable roller on its rocking frame toward the fixed roller, mechanism for rotating one of the pressure rollers and the take-up roller whereby rubber strip and liner is withdrawn from the supply roll and pressed against the fabric strip and the liner is discharged and wound up and the composite coated fabric strip moved forward.

10. The combination of a frame, two pairs of feeding rollers carried thereby, each pair comprising a roller on a fixed axis and a roller on a movable axis, the fixed-axis roller being the lower roller in one pair and the upper roller in the other pair, means for guiding a fabric strip to pass successively between the two pairs, means for looping two rubber strips around the two movable rollers, a driving motor having a sprocket wheel, and an endless sprocket chain engaging said sprocket wheel and sprocket wheels on the two rollers mounted on fixed axes.

11. An apparatus for applying a rubber strip to a fabric strip comprising a pair of rollers between which the fabric strip may pass, a roll having a wound-up course of rubber and having a liner which pass together in a loop about one of the rollers, mechanism for pressing one of the rollers toward the other roller to press the rubber strip against the fabric strip, mechanism for continuously rotating one of said rollers to feed the composite strip, a take-up roller for the liner after it has cleared the pressure roller about which the liner loops, and a spring belt for rotating the

take-up roller to wind up the liner while allowing slippage of the roller as the diameter of the wound-up material increases.

12. The combination of a servicer device having stock receiving rolls, a coating device adapted to coat a strip of fabric, means for continuously progressing the fabric strip through the coating device and towards the servicer device, other means for collecting the coated fabric onto the stock-receiving rolls of the servicer device at a rate faster than the fabric strip progresses through the coating device, and means coating with the coated fabric strip as it passes from the coating device to the servicer device to periodically interrupt the fabric collecting means and thereby make the ultimate progress of the coated strip substantially the same in both devices.

HENRY C. BOSTWICK.
